THREAD-ADVANCING REEL

Richard W. Stanley, Drexel Hill, Pa., assignor to
 American Viscose Corporation, Wilmington,
 Del., a corporation of Delaware

Application July 29, 1943, Serial No. 496,543

4 Claims. (CL 28—71.6)

This invention relates to thread-advancing reels which may be used for the production of a yarn store which is continuously advanced axially of the periphery of the reel during which time it may be subjected to fluid treatment in the manner and for the purposes conventional in the art.

It is a particular object of this invention to provide an improved thread-advancing reel. It is a further object of this invention to devise a reel which is adaptable to either a cantilever or double-end supported structure. It is a further object of the invention to provide a reel of this type based upon a structural principle, which, when embodied in a reel of large axial length, results in substantially uniform efficiency in thread-advancing action throughout the length of the reel, and at the same time is adapted to operation at high speeds of rotation of the reel. Further objects and advantages of the invention will be apparent from the drawings and description thereof hereinafter.

In the drawings, illustrative of the invention—

Figure 1 is a mid-section taken axially through one embodiment of the reel of this invention;

Figure 2 is a section taken on line II—II of Figure 1;

Figure 3 is a section taken on line III—III of Figure 1;

Figure 4 is a side view partially in cross-section of the cantilever form of the reel of this invention;

Figure 5 is an end view of the cantilever form shown in Figure 4; and

Figure 6 is a cross-section taken on line VI—VI of Figure 4.

Referring first to Figures 1 to 3, the thread-advancing reel comprises two sets of interdigitating bars, the bars 2 of one set alternating with and being spaced from and between the bars 3 of the other set. One of the sets comprising bars 2 is formed by suitably slotting the periphery of a housing formed of the telescoping hollow cylindrical members 4 and 5 secured together by the bolts 6.

This set of bars 2 is rotatably mounted concentrically on a stationary shaft 7 by means of ball bearings 8. The opposite ends of the shaft are provided with caps 9 suitably secured thereto, as by the screw threads shown, one being left hand and the other being right hand to prevent unscrewing during rotation of the reel. The outwardly projecting portions of the caps 9 have a non-circular periphery and are adapted to be supported in suitable supports or hangers 10 having sockets of corresponding cross-section to pre-

vent rotation. Packings 11 may be provided to prevent access of liquids to the bearings of the concentric cage or housing.

The other set of bars 3 are divided into several groups (three being shown) those of each group being formed integrally as radial projections from a casting occupying roughly a segment of a circle. Since these three units are identical, only one is described. The segment has a transverse web 12 extending in a plane substantially at right angles to the axis of the reel. The web has an opening 13 which is sufficiently large to allow plenty of clearance about the transverse bolts 6 which secure the housing or cage carrying the concentric bars 2. As shown in Figure 3, the web 12 is provided with a pair of bosses 14 extending axially to both sides of the web. The bosses 14 have bores within which pins 15 are secured by nuts 16. The enlarged ends 17 at the left of the pins 15 have shoulders bearing against a yoke 18 extending between the pair of bosses. The ends 17 are slidably mounted in bores through the spider 19 and the other ends of pins 15 are slidably mounted in similar bores of spider 20. A spring 21 within a recess in spider 20 midway between the bores pin-receiving therein normally presses the entire segment assembly to the left. A roller 22 secured to the yoke 18 bears constantly against the annular cam surface 23 of the fixed cam 24. The spiders 19 and 21 are clamped in their appropriate positions upon the sleeve 25 by nut 26, spacer sleeve 27 being inserted between the spiders. The sleeve 25 is carried by bushings 28 and 29, which in turn are carried by the centrally located eccentric portion 30 of the stationary shaft. A band 35 of member 4 beyond the bars 3 and having reduced diameter may serve as a surplus thread-collecting ring.

Flexible sealing membranes 31 and 32 may be secured to the segments, the central sleeve assembly, and the concentric cage members (as shown) where it is desired to use the reel for fluid treatment of yarns and the like, and to prevent the entrance of the fluid into the working parts of the reel.

In operation, the reel is supported in suitable supports 10 for maintaining the central shaft 7 stationary, and the concentric cage of bars 2 is driven by means of a gear 33 which meshes with gear teeth 34 formed or secured to one end of the concentric cage. The rotation of the concentric cage comprising bars 2 causes the rotation of the segment assemblies of bars 3 about the eccentric shaft 30. As a result of the fact that bars 3 rotate about an axis which is offset from

the axis of the bars 2, the thread-carrying surfaces of bars 3 alternately project outwardly and recede inwardly from the periphery formed by bars 2. At the same time, rotation of the segments carrying bars 3 with respect to the cam 24 causes axial motion thereof with respect to the bars 2. The arrangement of the eccentric portion 30 of the shaft and the cam surface 23 is so selected that shortly after bars 3 are caused to project outwardly from the periphery of the bars 2, the rise on the cam 24 shifts the bars 3 axially, which axial shift is maintained by a suitable dwell in the cam until after bars 3 have been caused to recede below the peripheral surface of bars 2, after which a drop in the cam surface 23 permits the spring 21 to return the segment to its original positions.

Referring to Figures 4, 5 and 6, a cantilever form of reel is shown comprising a concentric cage of bars 42 and the eccentrically mounted bars 43. Bars 42 are formed integral with an arcuate disc 44 which is secured for rotation with shaft 45, a gear 46 being keyed to the shaft for receiving and imparting rotatory motion thereto. The shaft is mounted for rotation within a suitable framework comprising the members 47 and 48. A sleeve 49 is secured to the frame member 48 by the nut 64 and in turn a cam 50 is keyed to the sleeve, thereby assuring the stationary position of cam 50. A housing comprising member 51 and flange 52 is mounted for rotation about the cam and encloses a spider having a plurality of axial bores 54 carrying plungers 55. The spider 53 rotates about the fixed sleeve 49, which has a cylindrical peripheral surface 66 which is eccentric to shaft 45, suitable bushings 57, 58, 59 and 60 being provided between the relatively rotating parts. Transversely of the central bore of the plunger 55, a pin 61 extends through slots 62 and is secured to the walls of the spider 53. To the outwardly projecting end of the plunger 55 is secured a segmental member having a plurality of bars 43. A spring 63 bears against pin 61 and against the bottom of the bore in the plunger 55 tending to bias the plunger with the segment carrying bars 43 to the right as viewed in Figure 4. The plunger 55 at the end opposite to that carrying the segment is provided with a roller 65 which bears against the cam surface 66 of the cam 50. A flexible sealing member 67 may be provided between the central portion of the spider 44, the segment members carrying bars 43, and the housing 51 and 52.

Operation of the cantilever form of the device is similar to that of the form supported at both ends. Rotation of shaft 45 causes rotation of bars 42 which rotation is transmitted thereby to the segment members and the spider member 53. Rotation of the spider member 53 about the eccentric surface 66 causes the alternate projection of bars 43 above the peripheral surface of bars 42 and recession thereof below the peripheral surface of bars 42. Simultaneously the action of cam surface 66 causes the axial motion of bars 43 in alternate directions at the time of protrusion and recession of bars 43 with respect to the peripheral surface defined by bars 42.

Whereas the actuated bars 3 and 43 of the invention have been shown assembled in groups upon a plurality of segmental members, it is to be understood that each of the bars 3 or 43 respectively may be mounted separately and may be provided with a cam follower to effect its individual actuation axially of bars 2 and 42 respectively by means of the fixed cam.

The construction of the reel of this invention is fundamentally simple, provision for axial movement and the spring control thereof serving to provide a motion which is smooth, positive and definitely controlled. The eccentric mounting of the actuating bars provides for uniformly efficient thread-advancing action throughout the length of the reel regardless of its axial length.

10 The various parts of the reel may be made of any desired material. Where it is desired to subject the filamentary material or yarns being handled to liquids which tend to be corrosive in nature, the various elements of the reel, especially the parts exposed to the liquid, may be made of such materials as Durez, Bakelite, stainless steel or the like.

15 Because of the fact that the bar members of the actuated cage (that is, the non-concentric cage) are mounted upon an eccentric surface, the axial length of the reel may be made as great as desired, without detrimentally influencing the thread-advancing efficiency along the surface of the reel.

20 While it has been stated above that the projecting members 3 of the reel of Figures 1 to 3 are generally supported in fixed positions by suitable bearings, a variation in the frequency of the advancing action of the actuating bars 3 may be obtained by rotating the central shaft having 25 the concentric portions 1 and the eccentric portion 30 about the axis of portions 1 in either direction with respect to the direction of rotation of the concentric cage carrying bars 2. By rotating this central shaft in the same direction, the frequency is decreased, while rotation of this central shaft in the opposite sense increases the frequency.

25 While specific embodiments of the invention have been described and illustrated, it is to be understood that changes and variations may be made without departing from the spirit and scope of the invention as defined by the appended claims.

30 I claim:

35 1. Reel mechanism comprising a set of spaced, longitudinally extending bar members rotatably mounted as a unit, a second set of spaced, longitudinally extending bar members alternating with those of the first set, supporting means for the second set rotatably mounted on an axis eccentric to the axis of rotation of the first set, the bar members of the second set being axially slidable with respect to the supporting means therefor, means for imparting relative rotation between the bar members and the eccentric axis, an annular cam secured in fixed relationship to the eccentric axis, cam follower rollers on the bar members of the second set and resilient means co-operating with the bar members of the second set to control the axial motion thereof in co-operation with the cam.

40 2. Reel mechanism comprising a set of spaced, longitudinally extending bar members rotatably mounted as a unit, a second set of spaced, longitudinally extending bar members alternating with those of the first set, a stationary member having an external peripheral surface eccentric to the axis of rotation of the first set, supporting means for the second set of bar members rotatably mounted on the eccentric surface, the bar members of the second set being axially slidable with respect to the supporting means therefor, means for rotating the sets of bar members, an annular cam secured in fixed relationship to the eccentric axis, cam follower rollers on the bar members of

the second set and resilient means co-operating with the bar members of the second set to control the axial motion thereof in co-operation with the cam.

3. Reel mechanism comprising a frame, a shaft rotatably mounted in the frame, a stationary sleeve mounted about the shaft and having an eccentric external bearing surface, a stationary annular cam, a set of spaced, longitudinally extending bar members secured for rotation with the shaft, supporting means for a second set of spaced, longitudinally extending bar members alternating with those of the first rotatably mounted on the eccentric bearing portion of the sleeve, said supporting means comprising axially slidable members each carrying at one end thereof a roller follower and at the other end at least one of the bar members of the second set and spring means for pressing said axially slidable members in co-operative engagement with the cam.

4. A cantilever reel supported at one end only thereof comprising a frame, a shaft rotatably mounted in the frame, a stationary sleeve mounted about the shaft having an eccentric external bearing surface, a stationary annular cam, a set of spaced longitudinally extending bar members, said bar members being supported on a substantially closed web secured for rotation with the shaft to its outermost end, supporting means for a second set of spaced longitudinally extending bar members alternating with those of the first rotatably mounted on the eccentric bearing portion of the sleeve, said supporting means comprising axially slidable members each carrying at one end thereof a part of the bar members of the second set and at the other end thereof a roller follower and spring means for pressing said axially slidable members into co-operative engagement with the cam.

the second set and resilient means co-operating with the bar members of the second set to control the axial motion thereof in co-operation with the cam.

3. Reel mechanism comprising a frame, a shaft rotatably mounted in the frame, a stationary sleeve mounted about the shaft and having an eccentric external bearing surface, a stationary annular cam, a set of spaced, longitudinally extending bar members secured for rotation with the shaft, supporting means for a second set of spaced, longitudinally extending bar members alternating with those of the first rotatably mounted on the eccentric bearing portion of the sleeve, said supporting means comprising axially slidable members each carrying at one end thereof a roller follower and at the other end at least one of the bar members of the second set and spring means for pressing said axially slidable members in co-operative engagement with the cam.

4. A cantilever reel supported at one end only thereof comprising a frame, a shaft rotatably mounted in the frame, a stationary sleeve mounted about the shaft having an eccentric external bearing surface, a stationary annular cam, a set of spaced longitudinally extending bar members, said bar members being supported on a substantially closed web secured for rotation with the shaft to its outermost end, supporting means for a second set of spaced longitudinally extending bar members alternating with those of the first rotatably mounted on the eccentric bearing portion of the sleeve, said supporting means comprising axially slidable members each carrying at one end thereof a part of the bar members of the second set and at the other end thereof a roller follower and spring means for pressing said axially slidable members into co-operative engagement with the cam.
